UNITED STATES PATENT OFFICE

MAURICE ANDERSON, OF MASON CITY, IOWA

LIFE PRESERVER SUIT

Application filed March 21, 1932. Serial No. 600,265.

The present invention relates to life preserving apparatus, and more particularly for a suit adapted to be worn by an individual so as to maintain the individual at the surface level of a body of water and which will admit of the proper supply of air and water to sustain the individual for a long period in the water if necessary.

An object of the present invention is to provide a relatively light simply constructed life preserver suit which may be quickly and easily fitted to an individual, and which is of improved construction to provide a flexible suit of great durability which is protected from cracking when folded, which is moisture and wind proof, which is very warm so as to prevent chilling of the individual in the water; which is practically puncture proof, and a suit constructed such that it will not rapidly deteriorate and will last over a period of years.

Another object of the present invention is to provide a suit the walls of which are constructed of a laminated fabric including a layer of rubber and a layer of "Cellophane" or similar relatively tough material adapted to reinforce and strengthen the rubber and prevent the same from cracking or breaking incident to folding of the suit when not in use.

Another object of the present invention is to provide a suit of this character with a normally deflated air pocket or ring surrounding the exterior of the suit and adapted to be inflated to the desired extent either before entering the water, or after the individual has taken to the water, and to provide an inflatable pocket or section of this character which is composed of material which is relatively strong, flexible and which possesses the various other features above enumerated in connection with the walls of the body portion of the suit.

The invention also aims at the provision of improved means for ventilating the helmet of the suit and for admitting air thereto, for admitting visibility from the front of the helmet and to supply drinking water to the individual within the suit.

With the foregoing and other objects in

view, the invention will be more fully described hereinafter, and will be more particularly pointed out in the claims appended hereto.

In the drawings, wherein like symbols refer to like or corresponding parts throughout the several views.

Figure 1 is a perspective view of a life preserver suit as worn and constructed according to the present invention.

Figure 2 is a fragmentary enlarged section taken through the upper forward part of the suit showing the air container, the water container and the adjacent structural parts of the suit.

Figure 3 is a detail further enlarged fragmentary view of the wall of the body portion of the suit, showing the various layers or laminations of which the wall is constructed.

Figure 4 is a detail perspective view of one of the shoes or foot coverings utilized at the lower end of the suit.

Figure 5 is a fragmentary perspective view of the upper end of the suit, showing the walls diagrammatically and showing the relative position of an individual to whom the suit is fitted.

Figure 6 is a further enlarged fragmentary view showing a section through the forward portion of the helmet and showing the relative positions of the upper end of the body of the suit on the lower end of the helmet.

Figure 7 is a fragmentary enlarged view through one side of the helmet, showing the ear shield and ventilator employed.

Figure 8 is a detail perspective view of the neck portion of the life preserving suit showing the waterproof neck fold therefor.

Referring now to the drawings, 10 designates the body portion of the life preserver suit which may be of any suitable configuration adapted to conform generally to the body and which may have its lower end bifurcated to provide a pair of leg portions 11, the lower ends of which are gathered in for engagement about the angle and are stitched or otherwise suitably and permanently secured within shoes 12, as shown particularly in Figure 4. The shoes 12 are of any suit.

able shape and construction and are provided with a suitable opening in their fore part, which opening may be closed by a sliding hook and fastener 13 and also by a plurality of straps 14 and buckles 15, as shown.

The body portion of the suit is also provided with arm portions 16 of suitable size to admit of the forcing of the hands and arms into the portion 16, and the lower ends of the portions 16 may be provided with integral mitts 17, or the like, adapted to receive the hands. The wrists 18 of the arm portions 16 may be contracted or gathered together in any suitable manner for holding the mitts 17 on the hands, but such portions 18 being of suitable size to admit of the forcing of the hands outwardly into the mitts 17.

The body portion 10 of the suit is provided with a laminated wall or walls which, as shown in Figure 3 preferably comprises a central layer 19 of "Cellophane" or similar tough flexible material impervious to air or moisture.

Cemented or otherwise suitably secured against the opposite sides of the "Cellophane" layer 19 are layers 20 of fabric of any suitable light and durable construction to provide a means of connecting outer layers to the "Cellophane" and which also serves as a cushioning and protecting layer at each side of the "Cellophane" to prevent damage thereto incident to the sharp folding of the suit when not in use. The fabric layers 20 also assist in offsetting penetration or puncturing of the wall of the body 10 incident to contact with sharp objects or the like.

To the outer fabric layer 20 is secured an outer layer of rubber 21 which is adapted also to resist passage of moisture or air through the wall of the suit, and which is also adapted to offset, together with the "Cellophane" layer 19, the transmission of heat back and forth through the wall of the suit. The inner layer 20 of fabric preferably carries a wool layer 22 of the desired thickness and texture to not only provide a soft lining for the inner side of the suit to prevent chafing or discomfort to the wearer, but to also add warmth to the suit so that where it is necessary to remain in the suit for a long period of time the wearer will not become chilled.

The upper end of the body portion 10 of the suit is provided with a suitable opening or fold 23 which is adapted to be closed by a suitable fastener 24, or the like, and which may be of any suitable construction or folding to admit of the stepping into the suit and drawing the same upwardly about the body and also admit of the quick and easy removal of the suit by a reverse operation.

Surrounding the body portion 10 of the suit between the waist portion thereof and the arm-pits, is an air container or ring 25 which is flexible and collapsible and which,

as shown particularly in Figure 2, is cemented or otherwise suitably secured at its lower edge against the outer surface of the body portion 10, which extends upwardly and is folded inwardly with its upper edge portion 70 turned downwardly and cemented or otherwise suitably secured to the body part 10 at a point above the waist portion of the suit. Sufficient fullness is given to the material of the air container 25 to permit the same to expand and extend outwardly about the suit for confining a desired amount of air for sustaining the suit with its occupant in a relatively upright position when in the water.

The wall of this flexible and deflatable air 80 container is preferably also of laminated construction with an intermediate layer 26 of "Cellophane" and with inner and outer layers 27 and 28 of rubber or like material. The air container is thus flexible, is impervious 85 to air and moisture, and may be somewhat distended or bulged outwardly under pressure of the air into substantially the position shown in Figures 1, 2 and 5.

The upper part of the air container is provided with a suitable air valve 29 which is located within easy reach of the wearer and preferably at the front of the suit, and attached to the air valve 29 is a hand pump 30 which may be cemented or otherwise suitably secured to the air container within easy reach of the wearer so that the air container may be inflated to a more or less extent even after the wearer has entered the water as the suit is designed to maintain the upper part 100 thereof projecting a sufficient distance out of the water to free the head and shoulders of the wearer.

The air container is also utilized for housing therein a water receptacle or container 31 which is preferably constructed of rubber and which may be of any suitable configuration. The water container is connected by means of a nipple 32 through the upper wall of the air container, as shown to advantage in Figures 2 and 5, and a tube 33, which is preferably flexible, is disposed through the nipple 32 with the lower end of the tube in the water container and with the upper end of the tube extending upwardly for positioning in the helmet of the suit so that the wearer may withdraw, by suction, drinking water from the container from time to time.

The suit is provided with a suitable helmet 34 shaped generally to the configuration of the head and which is provided in its front side with a curved frame or guide 35 which extends appreciably into the top of the helmet. A sliding door or sash 36 is mounted in the frame 35 and is provided at its lower end and outer side with a finger hold 36 adapted to be engaged by the hand for sliding the sash 36 upwardly into the top of the helmet 125 130

so as to admit air, and the like, through the front of the helmet when desired.

The lower end of the frame 35 is provided with a shield 38 of aluminum or other suitable material which is offset inwardly to overlap the lower end of the sliding sash 36 when the latter is closed, as shown in Figure 5. When the sash 36 is raised, air may enter the helmet for breathing purposes, and the shield 38 also serves to initiate or divide the air currents which may flow about within the helmet so as to more readily insure the breathing of pure air and the expulsion of air which has been breathed. The shield 38 also protects the mouth when the head is inserted in the helmet.

In each side of the helmet 34 there is provided a preferably circular ventilating and sound admitting opening 39. This opening 20 may be defined by an aluminum frame, or the like, of ring form and which carries at its inner side an aluminum shield or diaphragm 40 preferably covered at its inner side with leather or other suitable protecting material 25 41 adapted to register with the ear of the wearer, as shown to advantage in Figure 7. The opening in the frame 39 is preferably provided with a screen 42 of suitable mesh to prevent entrance of material or objects 30 floating about in the water. The upper part of the frame 39, between the shield 40 and the outer wall of the helmet 34, is provided with an air space which is protected by a screen 43 as shown in Figure 7. Thus, air 35 may freely enter through the opening or frame 39 into the space between the same and the shield 40. The air may rise through the screen 43 into the top of the helmet and may circulate therethrough in either direction.

The helmet 34 is preferably also constructed of a laminated sheet or wall, and as shown to advantage in Figure 7, the central or intermediate layer 44 is preferably "Cellophane" with an outer layer or covering 45 of rubber, and an inner lining or layer 46 of wool. The helmet 34 is properly spaced about the head by means of a semi-circular rubber block or strip 47 which may be secured about the back and opposite sides of the helmet in the interior thereof for engagement with the head so as to space the rear and side portions of the helmet from the head and relieve the ears from any pressure incident to the pressure of the helmet. The helmet 34 is provided at a lower portion with a spacing block 48 of rubber or other suitable material for engagement with the chin and the block 48 is adapted to cooperate with the block 47 50 for holding the helmet in position at all times.

The upper portion of the body 10 of the life preserver suit is provided with a gathered in neck part 49 which preferably has an outstanding flange 50 at its upper edge for receiving therebetween the inturned flange

51 of the helmet 34 so as to substantially interlock the body portion 10 with the helmet 34 when the split neck 52 of the helmet is closed about the upstanding neck portion of the body 10 by means of the strap or fastener 53, shown in Figure 1.

The lower end of the helmet may be provided with any suitably constructed apron 54 adapted to overlap the upper neck portion of the body 10 and cooperate therewith to effect a tight fitting joint between the body and the helmet. The frame 35 of the helmet 34 is provided with slotted guides 55 upon which is slidably mounted a vizor 56 which may be slid upwardly out of the line of vision 75 and out of the way of the front of the helmet when it is desired to slide the sash 36 into a more or less open position.

From the above description, it is thought the use of the life preserver suit will be thoroughly understood. The suit may be folded compactly into a small space, and when it is necessary to use the same it may be quickly extended and the user may step into the upper end of the suit and draw the suit upwardly about the body and then fold and close the upper port of the body by means of the slide fastener 24 or the like, and then the helmet 34 may be fitted over the head and over the neck 49 of the body portion of the suit. When the neck band 52 is drawn taut and secured by the fastener 53, the helmet is bound and sealed over the upper end of the suit. The shoes 12 may now be secured by means of the straps and buckles 14 and 15, and also by the slide fastener 13 to securely hold the lower end of the suit on the feet.

The pump 30 may now be operated, if there is time for such operation, so as to inflate the air container 35 to the desired extent. After entering the water, the pump 30 may be further operated to add more air to the container 25 so as to secure the desired buoyancy.

The individual within the suit may place the upper end of the tube 33 in the mouth and may from time to time draw drinking water which may be carried in the container 31.

The ear shield 40 not only protects the ear of the wearer but also serves as a trap for directing a current of the air in the upper part of the helmet 34 so that when water is impacted against the side of the helmet it will not strike the ear or the head but will strike against the shield and be deflected outwardly through the frame 29, and is also permitted to drain through the frame through one or more drainage openings 57 as shown in Figures 1 and 7.

The vizor 56 may be adjusted to protect the sash 36, and the latter may be provided with a pane of shatter-proof glass or other suitable substance to admit visibility through the front of the helmet. By sliding the sash 36 upwardly in the frame 35 more ventilation

is afforded the interior of the helmet, and access may be gained to the head of the occupant.

As shown in Figure 8 the neck portion 49 carries, in the opening 23 thereof, a sealing fold 58 adapted to be overlapped when the neck portion of the suit is closed and which may be of such size as to admit access to the suit when the neck portion is opened. The helmet 30 is sealed about the neck portion and this insures a tight water seal about the same.

It is obvious that various changes and modifications may be made in the details of construction and design of the above specifically described embodiment of this invention without departing from the spirit thereof, such changes and modifications being restricted only by the scope of the following claims.

What is claimed is:

20 1. A life preserver suit, comprising a flexible body portion, a helmet interfitting in the upper end of the body portion, said body portion and helmet having walls composed of laminated layers including a layer of "Cellophane."

25 2. A life preserver suit, comprising a flexible body portion having a wall composed of laminations including a layer of "Cellophane," a layer of rubber at the outer side of the suit, and a lining comprising a wool layer at the inner side of the suit.

30 3. A life preserver suit having a flexible body wall including a layer of "Cellophane," a layer of fabric on each side of the layer of cellophane, a layer of rubber at the outer side of the suit, and a layer of wool secured over the fabric at the inner side of the suit.

35 4. A life preserver suit, comprising a body portion having a flexible wall, an air container secured about the upper part of the body portion and comprising a flexible wall, and a helmet mounted on the upper end of the body portion, said body portion, air container and helmet composed of laminations 40 including a layer of "Cellophane" for increasing the strength of the respective walls.

45 5. A life preserver suit, comprising a body portion, a helmet detachably connected to the upper end of the body portion, lateral frames 50 mounted in the opposite sides of the helmet and having openings therethrough, shields carried by the helmet spaced inwardly from the said frames to receive impact of the water thereagainst and protect the head and for deflecting air upwardly through the openings into the top of the helmet, and spacing means carried within the helmet for engagement with the head to center the helmet on the head.

60 6. In a life preserver, a helmet having a guide frame extending upwardly in its front wall and into the top of the helmet, a vizor slidably mounted on the guide frame, a transparent sash mounted in the guide frame 65 adapted for adjustment beneath the vizor to

open and close the front of the helmet, and a deflecting shield carried upon the guide frame and spaced inwardly from the lower end of the sash in overlapping relation thereto for protecting the mouth when the head is inserted in the helmet.

7. In a life preserver suit, a helmet having a guide frame in the front wall thereof extending into the top of the helmet, a transparent sash slidably mounted in the guide frame, a vizor suitably mounted on the guide frame above the sash, spacing means arranged in the helmet for engaging the head to center the head therein, and air inlet traps mounted in the opposite sides of the helmet for protecting the ears and directing the head in the helmet.

8. A life preserver suit, comprising a flexible body portion, a flexible air container secured about the upper part of the body portion, an air valve secured through the upper side of said air container, a pump carried upon the air container at the outer side thereof and connected to said valve for supplying air to the container, a water container 85 mounted within the air container and adapted to contain drinking water, a helmet detachably connected to the upper end of the flexible body, and a tube extending from the lower portion of the water container upwardly into said helmet for supplying drinking water to the wearer of the suit.

In testimony whereof I affix my signature.

MAURICE ANDERSON.
